Primary Examiner — Mary Ann Calabrese*Assistant Examiner* — Natalya M Rapundalo(74) *Attorney, Agent, or Firm* — Dragon Sun Law Firm, PC; Jinggao Li, Esq.(57) **CLAIM**

The ornamental design for a solution mixer, as shown and described.

DESCRIPTION

FIG. 1 is a front, top, right perspective view of the solution mixer showing our new design;

FIG. 2 is a rear, bottom, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions of the solution mixer that form no part of the claimed design.

1 Claim, 8 Drawing Sheets(56)
